UNITED STATES PATENT OFFICE.

LEO PUNGS, OF BERLIN-CHARLOTTENBURG, GERMANY, ASSIGNOR TO C. LORENZ AKTIENGESELLSCHAFT, OF LORENZWEG, BERLIN-TEMPELHOF, GERMANY.

METHOD FOR HIGH-FREQUENCY TELEPHONY WITH OR WITHOUT A LINE.

Application filed August 23, 1921. Serial No. 494,570.

To all whom it may concern:

Be it known that I, LEO PUNGS, residing at Berlin-Charlottenburg, Germany, have invented certain new and useful Improvements in Methods for High-Frequency Telephony With or Without a Line (for which I have filed application in Germany on June 17, 1920), of which the following is a specification.

10 It has become known to use, for influencing high frequency currents for telephony with or without line, coils with iron cores whose magnetizing is varied from a microphone under interposition of strengthening tubes.

When the anode current of the tube is used directly for the magnetization a determined anode current is produced with the microphone not used for talking, the 20 so-called closed circuit current of the tube and consequently also a determined magnetization of the iron and of the coil. There exists for the coils a determined favorable closed circuit magnetization for the value 25 of which the magnetization produced by the talking currents must fluctuate.

According to the invention this closed circuit magnetization is adjusted to the most favorable value independently from the zero current of the tube by means of special auxiliary means. This can be effected in various manners. Either, besides the real winding, a second winding is used for the strengthened microphone currents, said second winding being fed with an auxiliary current. This auxiliary current is adjusted so that the resulting magnetization from auxiliary current and closed circuit current of the tube gives the desired most favorable value of the closed circuit magnetization. Or the high frequency winding can be utilized directly for the introduction of an auxiliary magnetizing current. In this case the switching-on of protecting choking coils and the like is required.

A still simpler means consists in adjusting the anode current of the tube when the microphone is not used for talking, to a value which produces the correct closed circuit magnetization in the iron. This is obtained by laying on the grid of the last tube a sufficiently great positive voltage which produces the desired anode current as closed circuit current. This voltage can be made adjustable. The winding upon the

iron core must be dimensioned accordingly. A separate winding and separate source of continuous current is under these circumstances not required for the auxiliary magnetizing current.

In the accompanying drawings in which like reference characters designate like parts throughout,

Figure 1 shows that form of the invention in which an auxiliary magnetizing winding is employed.

Figure 2 shows that form of the invention in which the magnetizing current for the core is derived from the anode current of the tube.

Figure 3 is a chart showing the relative values of grid voltage and current.

Fig. 1 shows a form of execution of the method by means of a separate auxiliary magnetizing winding. *a* is the coupling coil of the high frequency generator (e. g. machine, arc light, tubular sender). This coil *a* is fed from the high frequency generator arranged in the circuit in the usual manner and transmits the high frequency oscillations by inductive coupling to the antenna, as coil *a* has inductive coupled with coil *b*. *b* is the tuning coil in the antenna circuit, *f* the coil with iron core for the influencing of the telephony, *c* the high frequency winding, *d* the magnetizing current proper which is fed from the strengthening tube *g*. The grid of this tube is influenced in the well known manner across the transformer *h* from the microphone *k* which is inserted in the circuit of the battery *i*. When the microphone is not used for talking the current of the tube would adjust itself upon any value which corresponds with a grid potential determined by the voltage drop at the filament of the tube. This closed circuit current is given by the construction of the tube, the size of the same and so on. The given magnetization will not correspond with the most favorable value of the average magnetization but be much lower. In order to be able to adjust this most favorable value, a further winding *e* is provided, according to this invention, upon the iron core, said winding being fed across a resistance from a source of continuous current. Through adjustment of the current in this winding the most favorable value of the closed circuit magnetization in the coil can be determined. The winding is

preferably arranged so that it is not effective by the high frequency current.

In Fig. 2 another form of execution of the method is shown in which separate auxiliary winding and source of current are avoided. As already mentioned, the anode current is utilized for adjusting to the correct magnetizing value this being effected by the insertion of a voltage into the grid circuit, e. g. by means of a battery. This battery can evidently be small as it has almost no consumption of current. The inserted voltage is preferably made variable which can be effected by means of a cell-switch or of a potentiometer or the like.

Fig. 3 represents the known dependency between the grid voltage and the anode current in cathode tubes. When no grid voltage existed the anode current would adjust itself to the value J_0 or to a value which is only little different from this value. By the addition of a positive grid voltage E_g the anode current J_a is obtained. E_g must be selected in this case so that J_a produces the most favorable magnetization.

The examples cited do not exhaust the possibilities of executing the method as for example the two methods can be combined, that is to say special winding for the auxiliary magnetization and adjustment of the anode current by a positive grid potential. The independency from this normal closed circuit current of the tube is important. For greater efficiencies several tubes can be used in parallel connection, the grids of the tubes being then controlled by a common voltage.

I claim:—

1. In an apparatus of the character described, a source of high frequency currents, and means for influencing said high frequency currents, comprising a winding through which the high frequency currents may flow, a second winding, an iron core for said windings, an amplifying thermionic valve, said second winding being connected in series with the closed circuit of the valve, means for impressing signal representing currents upon the closed circuit of the valve, and means for adjusting the "no-load flux" of the core independently of the "no-load current" of the closed circuit of said valve.

2. In an apparatus of the character de-

scribed, a source of high frequency currents, and means for influencing said high frequency currents, comprising a winding through which the high frequency currents may flow, a second winding, an iron core for said windings, an amplifying thermionic valve, said second winding being connected in series with the closed circuit of the valve, means for impressing signal representing currents upon the closed circuit of the valve, and means including a source of direct current supply whereby the "no-load flux" of the core may be adjusted independently of the "no-load current" of the closed circuit of said valve.

3. In an apparatus of the character described, a source of high frequency currents, and means for influencing said high frequency currents, comprising a winding through which the high frequency currents may flow, a second winding, an iron core for said windings, an amplifying thermionic valve, said second winding being connected in series with the closed circuit of the valve, means for impressing signal representing currents upon the closed circuit of the valve, and an auxiliary winding upon the core, and a source of direct current for energizing said auxiliary winding.

4. In an apparatus of the character described, a source of high frequency currents, and means for influencing said high frequency currents, comprising a winding through which the high frequency currents may flow, a second winding, an iron core for said windings, an amplifying thermionic valve, said second winding being connected in series with the closed circuit of the valve, means for impressing signal representing currents upon the closed circuit of the valve, an auxiliary winding upon the core, a source of direct current for energizing the auxiliary winding, and choke coils to prevent high frequency current flowing through the auxiliary winding.

In testimony whereof I have signed this specification in the presence of two witnesses.

LEO PUNGS.
